UNITED STATES PATENT OFFICE.

FREELAND W. OSTROM, OF NEWARK, AND IRVING F. WEBB, OF ELIZABETH, NEW JERSEY, ASSIGNEES TO THE SINGER MANUFACTURING COMPANY, A CORPORATION OF NEW JERSEY.

FILLED-SACK-SEWING APPARATUS.

1,387,069.

Specification of Letters Patent. Patented Aug. 9, 1921.

Application filed January 24, 1918. Serial No. 213,504.

To all whom it may concern:

Be it known that we, FREELAND W. OSTROM and IRVING F. WEBB, citizens of the United States, residing, respectively, at Newark, in the county of Essex and State of New Jersey, and Elizabeth, in the county of Union and State of New Jersey, have invented certain new and useful Improvements in Filled-Sack-Sewing Apparatus, of which the following is a specification, reference being had therein to the accompanying drawings.

This invention relates to improved means for closing the mouths of filled sacks by a line of stitches and for conveying said sacks in an upright position under and past a sewing machine mounted on the main frame of the sewing and conveying apparatus and has for its object to, by the employment of an automatically controlled stitch-forming mechanism and automatically controlled means for holding in register the means for controlling the stitching operation with respect to the relative adjustment of the carrier and the sewing machine, lessen the cost of construction and effect increased production, together with the providing of a more conveniently operated apparatus better adapted to the requirements of machines of the present character.

In the accompanying drawings, which form a part of the specification, Figure 1 is a view in front side elevation of the present construction, the side guide-bar and conveyer-frame and carrier-belts slightly broken away, together with the electric switch-box in section. Fig. 2 is a plan view of the present construction with a portion of the carrier belts and table-top broken away for a better understanding of the means employed for automatically controlling the seam-formation. Fig. 3 is a view in end elevation of Fig. 2. Fig. 4 is a view in elevation of the sewing machine belt shifting mechanism, viewed in a direction opposite to that of Fig. 3, together with a portion of the sewing machine. Figs. 5 and 6 are views, in detail, of the right and left hand carrier-brackets, respectively, the former shown in section and the latter a plan view. Fig. 7 is a view, in detail, of a portion of the conveyer motor-bracket, illustrating the manner of securing it to the conveyer-frame. Fig. 8 is a fragmentary view of the means

employed for controlling the action of the stitch-forming mechanism and for suspending such action. Fig. 9 is a view, in detail, of certain of the elements employed for actuating the carrier belts, later to be referred to.

Referring to the drawings, the machine frame comprises the supporting standards or brackets 1 and 2 suitably secured upon the wooden base comprising the end pieces 3 and 4 into which are suitably secured the tie-pieces 5, 6 and 7, and upon said standards is suitably mounted the table-top 8 onto which is suitably secured the sewing machine bracket 9 having fixed to it the sewing machine head 10. Upon the bracket 11, mounted on said table-top, is suitably secured the electric motor 12 controlled by the electric switch 12', said motor acting, through the belt connection 13, to operate said sewing machine. As the stitch-forming elements herein employed are well understood it is not deemed necessary to specifically refer to the same.

The conveyer frame 14 is secured at nearly its opposite ends by screws, as 15, to the conveyer-frame brackets 16 and 17 which, in turn, are secured by screws, as 18, to the sliding nuts 19 and 20, respectively, the tightening of the screws 18 effecting a sliding fit between the surfaces 21 and 22 of the nuts 19 and 20, respectively, with the surfaces 23 and 24 of the standards 1 and 2, and between the surfaces 25 and 26 of said standards and the surfaces 27 and 28 of the brackets 16 and 17 respectively.

The electric motor 29 has a driving connection with the carrier belts 30 and 31 independent of the driving connections of the motor 12 with the sewing machine and is suitably secured on a bracket 32 carried by the frame 14, said motor being controlled by the switch 33 located in the switch-box 34. The conveyer-frame bracket 35 is suitably secured to the conveyer-frame 14 and provided with shaft-bearings 36 and 37 and bracket-lug 38, and into said bearings is journaled the friction-clutch driving shaft 39 on which is mounted a loose pulley 40 carrying the cup-shaped disk 41, said pulley and disk being operatively connected, by belt 42, with the motor 29. A cone-shaped pulley 43 is suitably secured on the shaft 39 to rotate therewith and is adjustable in the di-

rection of the length of the latter. Upon the lug 38 is suitably fulcrumed a clutch-adjusting bar 44 acting in opposition to the resiliency of the clutch spring 45 to, at the 5 will of the operator and in a manner later to be explained, force said cone-disk into contact with the inner inclined surface 45' (shown in dotted lines only) of the disk 41, thus effecting power transmission from the 10 motor 29 to the shaft 39.

A gear-shaft 46 is journaled in an upright position in the bearings 47 and 48 formed on the bracket 35 and at its upper end carries a beveled gear 49 meshing with 15 a like gear member 50 carried by the shaft 39, said gear shaft being provided with a worm-gear 51 meshing with a gear member 52 fast on the shaft 53 journaled in the bearing 51' and in suitable bearings formed 20 in the frame 14 and carrying the belt driving cylinder 54, provided with the rib 55 for directing the belts 30 and 31 in a given line of travel, a like cylinder 56 provided with a rib 55' being suitably journaled in the 25 opposite end of the frame 14 and acting as an idler for the travel of said belts, the latter supported between said cylinders by rollers, as 57, except as noted later.

A treadle rock-shaft 58 is journaled in 30 suitable bearings formed in the bearing brackets, as 59, suitably secured upon the frame base and to the forward end of said shaft is suitably secured a bracket-arm 60 into which is suitably secured a treadle-rod 35 61 provided with a treadle member 62, and to resiliently hold said treadle mechanism in the position shown in the drawings, said rock-shaft has suitably secured on it an arm 63 and a spring 64, the free end 65 of the 40 latter bearing on the tie-piece 7 with its end 66 in contact with the arm 63, thus forcing the stop member 67 in contact with the tie-piece 7. A treadle shaft crank-arm 68 fast on the rock-shaft 58 and at its free end is 45 linked to a chain connection 69 passing around an idler 69' and having its opposite end linked to an arm 70 projecting from a rocking standard 71 journaled at its opposite ends in bearing-lugs, as 72, one of which 50 is suitably secured to the under side of the table-top and the other upon the tie-piece 5, said rocking standard carrying a parallel bar 73 which, in practice, acts on the lever 44 to move the clutch-member 43 in engagement with the disk 41.

To adjust the conveyer frame to meet the requirements of sacks of varying sizes, there are threaded through the nuts 19 and 20 vertically arranged screw-threaded rods 74 60 and 75, respectively, having their upper ends journaled in suitable bearings, as 76, (one only of which is shown, see Fig. 3) carried by the standards 1 and 2, respectively, the upper ends of each of said rods 65 being provided with a gear member, as 77,

meshing with like gear members, as 78, (one only of which is shown) provided with the respective crank-shafts, as 79 actuated, through the crank-members, as 80, to effect the desired vertical adjustments of said conveyer-frame. 70

Referring now to the means employed for controlling the stitching operations, 81 represents a belt-shifting bracket suitably secured to the machine bracket 9 and provided with a lug 82 upon the free end of which is pivotally mounted a belt-shifting lever 83 provided with belt-shifting fingers, as 84, a belt-shifting weight 85, a brake-member 85' and a flexible connection supporting and directing element 86 the bracket 81 being provided with a flexible connection directing element 87 and a flexible connection supporting and directing element 88, the latter preferably secured against movement. The power-transmitting and arresting trip mechanism preferably comprises the bars 89 and 89' having their ends 90 connected with the trip-bar crank-arm 91 fast on one of the roller-rods, as 92, of the rollers 57, the rods 90 being mounted to revolve on pintle screws, as 93, secured against accidental movement by the nuts, as 94, the opposite ends of the bars 89 and 89' being pivotally connected with the roller-rod crank-arm 96 fast on 95 the roller-rod 97, which latter is journaled in suitable bearings formed in the frame 14 and at its inner end carries a flexible connection actuating crank-arm 98 linked to one end of a flexible connection 99 which passes over 100 the element 86, carried by the belt shifting lever 83, under the element 87 and over the element 88 mounted on the bracket 81, the opposite end of said flexible connection having attached to it a suspended weight 100 105 acting as a resistance member to the rocking movements of the crank-arm 98, the movements of the latter being limited in one direction by the stop-rod 101 fast on the roller-rod 97 and stop finger 102 secured in 110 the frame 14, the belt supporting rollers, as 103, being of the same construction and support as the rollers 57 except that the latter comprise a two-part construction of tubular wood to accommodate the action of the trip-bar 89—89'. 115

In the operation of the present construction, the operator adjusts the electric switches 12' and 33 to start the motors 12 and 29, respectively. When the treadle 120 mechanism (60, 61 and 62) is adjusted to the left (see Fig. 1) which, through the connections pointed out, moves the rod 73 into contact with the power-transmitting clutch-adjusting lever 44 acting on the cone-pulley 125 43 to engage the latter with the disk 41 and drive the shaft 39, which latter through the gear members 50, 49, 52 and cylinder 54, transmits motion to the carrier belts 30 and 31. The conveying mechanism now being 130

in operation the filled sack 7 is placed on the carrier belts in substantially the position shown in dotted lines, Fig. 2, and in its travel it contacts with and rides the trip-bar 5 89 which moves the latter downward into the space provided between the inner ends of the tubular wood pieces carried by the roller-rods 92, said movement of the trip-bar, through the crank-arm 98 and flexible connection 99, acting to rock the belt-shifting lever 83, and through the belt-shifting fingers 84, shift said belt from the sewing machine loose pulley 105 to the tight pulley 106, thus transmitting power to the commonly employed main-shaft (not shown) of the sewing machine, the resistance member 100 holding said flexible connection in substantially its normal or position of rest between said members and the disk 99. As the sack is 10 carried out of engagement with said trip-bar the weight 85, carried by the belt-shifting lever, returns the belt 13 to said loose pulley and moves the trip-bar to its normal or elevated position, followed by like operations 15 and control for each subsequent conveying and stitching operation. 106 represents a side guide-bar for retaining the bags in their upright position as they are conveyed past the sewing machine head.

From the foregoing it is to be understood that there is a unit construction and drive for carrying the bags past the sewing machine head and a second unit of construction and drive for effecting and controlling 20 the seam-formation, the former manually and the latter automatically controlled, said automatic control insuring that only such length of seam will be formed as is required to close the sack mouth.

There is employed in the present construction a manually controlled thread-cutter, substantially the same as is illustrated in U. S. Patent No. 1,156,821, of October 12, 1915, to A. Rontke, but as such construction forms 25 no part of the present invention and is commercially common it is not thought necessary to specifically illustrate and describe the same as the patent above referred to, together with the illustration of the shear-operating lever 107 (see Figs. 1 and 2) is sufficient for an understanding of its construction and application by those conversant with the art.

Having thus set forth the nature of the 30 invention, what we claim herein is—

1. In a filled sack sewing apparatus, in combination with seam-forming and sack-conveying mechanisms, and driving means for said mechanisms, of work-controlled 35 means for effecting action and inaction of one of said mechanisms, and manually operable means for arresting the action of each of said mechanisms independently of the other mechanism.

2. In a filled sack sewing apparatus, seam-

forming mechanism, sack-conveying mechanism, driving means for each of said mechanisms, manually operated means for controlling the sack-conveying driving-means, and work-controlled means for effecting action 40 and inaction of the seam-forming driving means permitting the continuance of an initiated seaming operation during the inactivation of the sack-conveying mechanism.

3. In a filled sack sewing apparatus, a stitch-forming mechanism, a sack-conveyer frame, a sack-conveyer, and a trip-mechanism for controlling the action and inaction of said stitch-forming mechanism, said frame, conveyer and trip-mechanism located 45 below the plane of travel of a filled sack.

4. In a filled sack sewing apparatus, seam-forming and sack conveying mechanisms and means including a trip-mechanism located below the line of travel of the filled sack being acted on for automatically effecting and for discontinuing the seam-formation, and manually operated means for controlling the action and inaction of said conveyer mechanism.

5. In a filled sack sewing apparatus, the combination with a sewing machine, a conveyer-frame to receive the filled sacks, carrier-belts supported upon said frame and adapted to move a filled sack along the upper face of said frame and past the sewing machine, of means including a trip-mechanism located below the line of travel of the filled sack for automatically effecting and for discontinuing the seam-formation.

6. In a filled sack sewing apparatus, the combination with a sewing machine, a conveyer-frame to receive the filled sacks, carrier-belts supported upon said frame and adapted to move a filled sack along the upper face of said frame and past the sewing machine, of means including a trip-mechanism located below the line of travel of the filled sack for automatically effecting and for discontinuing the seam-formation, together with means for relatively adjusting the sewing machine and frame to accommodate sacks of varying sizes.

7. In a filled sack sewing apparatus, seam-forming and sack-conveying mechanisms, the latter mechanism including a conveyer-frame provided with a multiple of carrier-belts and means, including a power transmitting and arresting trip-mechanism, carried by said conveyer frame for automatically controlling the time and extent of seam-formation.

8. In a filled sack sewing apparatus, seam-forming and sack-conveying mechanisms, the latter mechanism including a conveyer-frame provided with a multiple of carrier-belts, the former mechanism including a sewing machine provided with means directly connected with the latter for, at times, driving said machine, a power transmitting 125 driving said machine, a power transmitting 130

and arresting trip-mechanism carried by said conveyer-frame and connections for operatively connecting said trip-mechanism with said means for driving the sewing machine.

9. In a filled sack sewing machine apparatus, a sewing machine comprising a stitch-forming mechanism and means for driving the same and a sack-conveying mechanism and means, independent of the former means, for driving said conveyer mechanism, the former means including a power transmitting and arresting trip-mechanism automatically controlled to effect and arrest the action of said stitch-forming mechanism, the latter means including twin belts for carrying filled sacks past the said sewing machine, one of said belts being located at one and the other at the opposite side of said trip-mechanism.

10. In a filled sack sewing apparatus, seam-forming and sack-conveying mechanisms, the latter mechanism including a conveyer-frame and carrier-belt, the former mechanism including a sewing machine provided with means directly connected with the latter for, at times, driving said machine and a power transmitting and arresting trip-mechanism carried by said conveyer-frame and connections including a belt shifting lever and a flexible connection, the latter operative for a portion of its length to transmit rocking movements to said belt shifting lever, the balance of its length remaining substantially at rest for operatively connecting said trip-mechanism with said means for driving the sewing machine.

11. In a filled sack sewing apparatus, seam-forming and sack-conveying mechanisms, the latter mechanism including a conveyer-frame and carrier-belt, the former mechanism including a sewing machine provided with means directly connected with the latter for, at times, driving said machine and a power transmitting and arresting trip-mechanism carried by said conveyer-frame and connections including a belt shifting lever operatively connected with a flexible connection secured at one end to said trip-mechanism and at its opposite end to a resistance member for operatively connect-

ing said trip-mechanism with said means for driving the sewing machine.

12. In a filled sack sewing apparatus, seam-forming and sack-conveying mechanisms, the latter mechanism including a conveyer-frame and carrier-belt, the former mechanism including a sewing machine provided with means directly connected with the latter for, at times, driving said machine and a power transmitting and arresting trip-mechanism carried by said conveyer-frame and connections including a flexible connection a belt shifting lever and flexible connection directing and supporting elements for operatively connecting said trip-mechanism with said means for driving the sewing machine.

13. In a filled sack sewing machine, a stitch-forming mechanism, a sack-conveying mechanism including a conveyer frame, a sack-conveyer comprising spaced carriers, and a trip-mechanism located intermediate the latter.

14. In a filled sack sewing machine, a stitch-forming mechanism, a conveyer-frame, a conveyer, and a trip-mechanism carried by said frame controlled by the travel of a filled sack to effect and arrest seam-formation.

15. In a filled sack sewing machine, a stitch-forming mechanism, a conveyer-frame, a conveyer, a trip-mechanism carried by said frame controlled by the travel of a filled sack to effect and arrest seam-formation, and manually operated means for controlling the action and inaction of said conveyer.

16. In a filled sack sewing machine, a stitch-forming mechanism, a conveyer-frame, a conveyer, a trip-mechanism carried by said frame controlled by the travel of a filled sack to effect and arrest seam-formation, and means for permitting a relative adjustment of the sewing machine and conveyer-frame to accommodate sacks of varying sizes.

In testimony whereof, we have signed our names to this specification.

FREELAND W. OSTROM.
IRVING F. WEBB.
